UNITED STATES PATENT OFFICE.

HENRY EDMUNDS, JR., OF NEW YORK, N. Y., ASSIGNOR TO THOMAS J. MONTGOMERY, OF BOSTON, MASSACHUSETTS.

SWITCH FOR ELECTRIC LAMPS.

SPECIFICATION forming part of Letters Patent No. 290,406, dated December 18, 1883.

Application filed April 5, 1883. (No model.)

To all whom it may concern:

Be it known that I, HENRY EDMUNDS, Jr., of the city, county, and State of New York, have invented an Improvement in Switches 5 for Electric Lamps; and the following is declared to be a description of the same.

This invention relates to switches for turning on and off the electric current in incandescent electric lamps, and the same are adapted to chandeliers or brackets in either new 10 work or what is termed "adapted fittings."

The object of my invention is to make the switch positive in its action, simple in construction, and one in which the key will be 15 held firmly in position when the current is turned on or off. I employ a metal cup having a connection at one or both sides for the chandelier or bracket and the incandescent electric lamp. Into this cup I place a base of 20 non-conducting material—such as rubber, gutta-percha, or vulcanite fiber—with a hole through it for the passage of one circuit-wire. Upon the surface of this non-conducting material are plates of metal with binding-screws 25 for the circuit-wires and spring-arms, and I provide a key for making and breaking the electric circuit between these springs. There is a cover to said cup, and through it the spindle of a turn button or handle passes for operating said key in lighting or extinguishing 30 the lamp.

In the drawings, Figure 1 is an elevation of an incandescent electric lamp holder, socket, and switch. Fig. 2 is an elevation or face 35 view of the switch with the cover removed. Fig. 3 shows the inner surface of the cover. Figs. 4 and 5 are modifications of the form of the switch-springs, and Fig. 6 is a section of the switch shown in Fig. 5. Fig. 7 represents my improved switch as attached to the 40 barrel of the cock in a gas-pipe; and Fig. 8 represents my switch as applied to the distribution-box of a chandelier.

Fig. 1 illustrates a lamp, its holder or socket 45 e' , and the exterior form of the switch handle and case. The lamp itself, however, is to be of any desired character, as it forms no portion of my present improvements. The body of the cup a and the pipes b b' are preferably 50 made as one; but they may be separate, as hereinafter shown, and the outer part of the

cup has a screw-thread within it, which engages the thread upon the cap or cover c . The non-conducting base d fits into this cup a , and it is fastened tightly, and it usually has a 55 hole through it for one circuit-wire, 4, to pass, as seen in Fig. 6.

In Figs. 2, 3, 4, and 5 the non-conducting material is indicated by the close parallel lines. In Fig. 2 the spring-arms e e' are coiled around 60 the posts f f' , set in the non-conducting material, and pass to the clamping-screws g g' . The plates of metal h h' connect the clamping-screws g g' with the binding-screws i i' , and to these binding-screws i i' the circuit-wires 2 are 65 attached. The spring-arm e' is limited in its inward movement by the stop k . In Fig. 4 the plates h h' are shown of larger size, and made as segments of a circle, and the binding-screws i i' , to which the circuit-wires 2 are secured, as 70 shown upon said plates. In this figure the spring-arms e e' are sustained by the posts f f' , but are of a different shape from those of Fig. 2, and the springs l l' , which are held and supported by lugs and pins m m' , formed upon the 75 plates h h' , press upon the arms e e' , but allow them to yield. The arm e' is retained by the stop k , as in Fig. 2. In Fig. 5 the plates h h' are made of a similar shape to those in Fig. 4, and the binding-screws i i' for the circuit-wires 80 2 are secured upon said plate in the same manner. The arm e is made double, as shown, and passes around the clamping-screw g and partly around the binding-screw i . The free ends of said arm e act as springs, and yield to 85 the pressure of the key when turned. The spring e' is of bent form, and is held in position by the clamping-screws g . The plate h of this figure forms a support for the center of the key n , and the position of this key is 90 shown in Figs. 2, 4, and 5 by dotted lines as turned off. The position when turned on will be at right angles thereto. The spindle o passes through the cover c into a block, p , of insulating material, to which the key n is also 95 secured by projections, that pass into the block p at a distance from the spindle o . This cover c , key n , and block p are shown in Fig. 3. The spindle o is provided with a handle, o' . The main wire in all of these forms is continued 100 through the non-conducting base d , and the return-wire is divided and carried to the bind-

ing-screws $i i'$, the circuit being made as the key n is turned between the springs or arms $e e'$, and its edges brought forcibly into contact with such springs or arms to partially press them apart, and thus insure perfect metallic continuity for the electric circuit. When the key is turned so as to stand in the position represented in Figs. 2, 4, 5 by dotted lines, the circuit is broken and the spring e holds the key in position by pressing against one of its sides.

My improved switch can be used at the ordinary gas-cock, as shown in Fig. 7, in which case I remove the plug of the cock and provide a spindle upon the base of the cup a , and this spindle is passed through the barrel of the gas-cock, and I secure said spindle and cup by a nut, as shown. The wires for the electric circuit are passed through the barrel, as illustrated in said figure. My improved switch can also be employed at the distribution-box of a chandelier, as shown in Fig. 8, the switch-case forming the ornamental base of said distribution-box cover. In this instance I divide the direct conductor, carrying it through said switch, so that the turning on or off of the switch either lights or extinguishes all of the lamps upon the chandelier. I prefer to employ this switch at the distribution-box, in addition to a switch for operating each individual lamp.

I claim as my invention—

1. In a switch for electric lighting purposes, the combination, with the cup a , cover c , and non-conducting base d in the bottom of the cup, of the arms $e e'$ at opposite sides of the center of the base, the studs $f f'$, clamping-

screws $g g'$, plates $h h'$, and binding-screws $i i'$, connected to and supported by the base d , and key n , with a shank passing through the cover 40 for making and breaking the circuit, substantially as set forth.

2. In a switch for electric lighting purposes, the combination, with the cup a , cover c , and non-conducting base d within such cup, of the arms $e e'$, studs $f f'$, stop k , plates $h h'$, binding-screws $i i'$, connected to and supported by the non-conducting base, and the key n , between the arms $e e'$, for making and breaking the electric circuit, substantially as set forth. 45

3. A switch for electric lighting purposes, composed of a cup, a , a non-conducting base, d , within the cup, perforated for the passage of the direct wire, and provided with spring-arms upon the surface of the base, and binding-screws for the return-wire, and a key between the arms for turning on and off the electric current, substantially as set forth. 55

4. In a switch for electric lamps, the key n , formed of a metal plate with prongs, the insulating-block p , into which such prongs penetrate, the spindle o , passing into the block between the prongs, but not touching them, a point projecting from the key, the insulating-base d , springs or arms $e e'$, and circuit-connections to the same and the case and cover, substantially as set forth. 60

Signed by me this 29th day of March, A. D. 1883.

HENRY EDMUNDS, JR.
